UNITED STATES PATENT OFFICE

119,895

DESIGN FOR A SPOON OR OTHER ARTICLE OF FLATWARE

Ernest William Walker, Concord, N. H., assignor
to Concord Silversmiths, Ltd., Concord, N. H.,
a corporation of Delaware

Application December 2, 1939, Serial No. 88,633

Term of patent 14 years

To all whom it may concern:

Be it known that I, Ernest William Walker, a citizen of the United States, residing at Concord, in the county of Merrimack and State of New Hampshire, have invented a new, original, and ornamental Design for a Spoon or Other Article of Flatware, of which the following is a specification, reference being had to the accompanying drawing, forming a part thereof.

Figure 1 is an elevational view of a spoon showing my new design.

Figure 2 is a side elevation of the spoon shown in Figure 1.

Figure 3 is a sectional view on the line 3—3 of Figure 1, this view being on a larger scale.

Figure 4 is a section on the line 4—4 of Figure 1, the scale being the same as that shown in Figure 3.

I claim:

The ornamental design for a spoon or other article of flatware, as shown.

ERNEST WILLIAM WALKER.
